CLAIM

The ornamental design for an electronics enclosure, as shown and described.

DESCRIPTION

FIG. 1 is a perspective view of an electronics enclosure depicting a new design;

FIG. 2 is a front view thereof;

FIG. 3 is a back view thereof;

FIG. 4 is a side view thereof;

FIG. 5 is an opposite side view thereof;

FIG. 6 is a top plan view thereof;

FIG. 7 is a bottom plan view thereof; and,

FIG. 8 is an additional perspective view thereof.

(Continued)

The broken line portion of the figure drawings is included to show unclaimed subject matter only and forms no part of the claimed design.
